Primary Examiner — Mark T. Philippss

(57) **CLAIM**

The ornamental design for a cutting insert for machine tools for metalworking as shown and described.

DESCRIPTION

1. Cutting insert for machine tools for metalworking

1.1 : Perspective

1.2 : Front

1.3 : Back

1.4 : Top

1.5 : Bottom

1.6 : Left

1.7 : Right

When viewed from a top view, this design features a long bar-shaped central section with circular sections connected to both ends; at the center of each circular section, there is a star-shaped feature with four points, surrounded by circles; additionally, when viewed from a front view, the central section protrudes upward relative to the circular sections; when viewed from left and right views, the central section possesses a V-shaped notch.

1 Claim, 7 Drawing Sheets
